DEVICE FOR FEEDING AND CONTROLLING THE FLOW OF MATERIALS

Filed Jan. 8, 1929

By: Marks & Clark
Attn:

UNITED STATES PATENT OFFICE

WILLIAM ROSS, OF SURBITON, ENGLAND

DEVICE FOR FEEDING AND CONTROLLING THE FLOW OF MATERIALS

Application filed January 8, 1929, Serial No. 331,106, and in South Africa January 11, 1928.

This invention relates to the feeding and controlling of the flow of materials such as coke, coal, stone, sand, ore, or other granular or pulverulent or like material whether the same be free running or sticky or reluctant, and whether the material is to be delivered from storage bins or other receptacles or whether the devices are to be employed for accelerating, retarding or stopping the flow of materials already in motion.

So far as relates to the natural flow of materials from the opening of storage bins and the like it will be clear that such flow will vary according to whether the material is small or large or whether it is mixed and varying in size and also with the shape of the material and upon its running qualities, that is to say, whether it is clean and free-running or sticky and reluctant. An operator engaged in lifting and lowering a slide gate to suit these changes in the material and maintain an even tonnage flow must be very quick and however skilled he may be it is exceedingly difficult for him properly to control the flow since, for example, one large piece of material may prevent the lowering of the gate in a manner which would be required to stop the rapid flow of small material.

So far as relates to material already in motion, such as in an open chute or slide, high velocity of flow may be detrimental in many ways and especially in the case of coal, coke and like friable materials it would lead to breakage of the material during motion and when brought suddenly to rest at its destination. Moreover, a change or changes of material may on the other hand decrease the speed so that the material will either overflow the sides of the chute or slide or its flow will be entirely arrested.

The object of the present invention is to provide a simple and efficient form of feeding and control device which will give automatically proper control of the flow of materials under all the above conditions or under other conditions that may be met with in practice and which will enable the flow opening or outlet of bins to be made of ample dimensions to ensure the passage of material

without bridging or jamming while at the same time providing for any necessary adjustments that may be required to be made to suit varying changes in the material or to suit tonnage changes that may be required.

The invention consists in a feeding and control device for materials comprising a plurality of flexible chain members adapted to move in a circular, elliptical, elongated or other path and yielding or movable in relation to the material and to the outlet or opening through which the material is to flow or is flowing and adapted automatically to adjust themselves to the character of the material or to the varying conditions under which they are required to work.

The invention also consists in a feeding and control device of the above character in which the chain members are driven from one end by a plurality of bars carried upon a rotary member or members.

The accompanying drawing illustrates one convenient mode of carrying out the invention.

Figures 1 and 2 are respectively a sectional elevation and a front elevation of one form of apparatus in accordance with the invention.

Figure 3 is a view illustrating a part of Figure 1 on a somewhat larger scale and

Figure 4 is a side sectional elevation of a part of Figure 3.

Figure 5 is a sectional elevation of one form of chute in accordance with this invention, and

Figure 6 is a front elevation of a modified form of flexible element in accordance with this invention.

In carrying my invention into effect in one convenient manner as, for example, in its application to the control of the flow of material from a storage bin I arrange for the outlet opening a feeding and control device comprising a plurality of chains or like flexible members *a*, the links of which engage with bars *b* or other device by which the chains may be moved for the purpose of controlling the flow of the material. The bars *b* are carried in end discs *c* mounted upon a shaft *d* which is rotatably mounted in suit-

able bearings (not shown) and in operation the chains move in such a direction and at such a speed that the material in the chute or slide will move in the same direction and at substantially the same speed. When an unduly large piece of material arrives at the feed device the latter will yield to it owing to its flexible character and will permit it to pass, afterwards returning to its normal working position.

When in operation the device will yield readily to give passage to large pieces of material even though the device and the members composing the same be very heavy, this yielding being due to the fact that the movement of the device is arrested momentarily at the large pieces of material and the chains therefore slacken above that point, the chain link construction of flexible feeding device permitting superficial adjustment of such device as distinguished from the form of feeding device disclosed in my prior U. S. Patent No. 1,651,633 which although flexible and able to adjust itself to varying conditions is not capable of independent adjustment throughout its cross section or transversely. When not in motion, however, there is no such special yielding capacity in the device and the whole mass of the device therefore operates to resist the passage of the material and to stop the flow.

The bars *b* are arranged to have sufficient grip of the chains to drive them under ordinary working conditions but should any exceptional condition occur in the chute such as seriously to obstruct the movement of one or more of the chains the bars *b* will readily slip on such chain or chains and cease to drive them but will continue to drive the other chains in the usual way, and it will be evident that all the chains may cease to move without causing any serious wear upon the bars *b*.

In order to provide for adjustment of the bars *b* radially in relation to the rotary member or members carrying the same so as to enable them accurately to fit the chains I arrange for the ends of the bars *b* to pass into radial slots formed in the end discs *c*, the position of the bars in such radial slots being adjustable as, for example, by means of adjusting screws *e* or by any other suitable or well-known means.

It is sometimes desirable to shut off the flow at the lower end of the chute for a short time while the wagons or skips which are receiving the material are shifted and this may conveniently be effected by means of a slide gate or the like at the lower end of the chute without stopping the feeding device in which case the chains will simply slip on the top of the material in the chute or the bars *b* will slip on the chains.

I may employ a tapering chute, wide at the top end to avoid as much as possible

jamming or bridging of the material at the hopper outlet and narrow at the lower end to fit the crusher or other relatively narrow machine or device to which the material is being fed and in cases where the width at the lower end may be insufficient to accommodate the chains I may vary the lengths of the chain orbits so that there will be fewer chain elements at the lower end of the chute than at the upper end.

It is, however, to be understood that the foregoing details of construction are given purely by way of illustration and not of limitation since I may vary the number and mode of disposition of the chain devices, the means adopted for driving the same and the manner of arranging the same in relation to the opening or channel through or along which the material is to flow as well as the means adopted for rotating the feed device either by hand or by power depending upon the character of materials to which the invention is to be applied or any practical requirements that may have to be fulfilled.

Figure 5 illustrates a modified form of chute which may be employed in accordance with the invention, the bottom of the chute *f* being provided with apertures *g* which permit material of a predetermined size to pass therethrough and also with other smaller apertures *h* which permit the passage of smaller material than a predetermined size. Figure 6 illustrates a modified form of feeding device in accordance with the invention and according to which the chains *a* are fastened together at a plurality of points *j*.

Having now described my invention what I claim as new and desire to secure by Letters Patent is:—

1. Mechanism for controlling the flow of granular or pulverulent or like material comprising in combination an inclined chute having apertures therein of varying sizes and formed with a taper at its lower end, a rotary member disposed above the chute adjacent its upper end and a flexible mat carried on said rotary member, said flexible mat being composed of a plurality of endless chains united together so as to form a unit which is flexible both longitudinally and transversely and being arranged to bear upon the material on the chute for a substantial portion of its under surface so as to drag upon the material and so control and feed same.

2. Mechanism for controlling the flow of material comprising in combination a chute along which the material is adapted to move, a device rotatably mounted above a portion of the chute, said device having bars extended radially beyond said device and spaced therearound, flexible chains each having links with rounded ends adapted to

pas over said bars with alternate links resting flatwise upon the bars, the adjacent links on either side of a bar lying in planes at an angle to the bars to locate the rounded 5 ends of adjacent links against the bars whereby the rounded portions of the links may pass over the bars when too much resistance is offered to movement of the chains by the bars.

10 3. Mechanism according to claim 2 comprising means for adjusting the positions of said bars radially in respect to the axis about which they rotate.

15 In testimony whereof I have signed my name to this specification.

WILLIAM ROSS.
